United States Patent Office

Des. 221,743
Patented Sept. 7, 1971

221,743

SLEEPER VAN

Kenneth O. Cunningham, 3948 Adams 83704, and Ray
Montgomery, Rte. 2, Dalton Lane 83702, both of
Boise, Idaho

Filed Mar. 9, 1970, Ser. No. 21,830

Term of patent 14 years

Int. Cl. D12—16

U.S. Cl. D14—3

FIG. 1

FIG. 2

FIG. 3

FIG. 4

FIG. 5

FIG. 6

FIG. 1 is a right side elevational view of the sleeper van embodying our new design;

FIG. 2 is a left side elevational view;

FIG. 3 is a rear elevational view;

FIG. 4 is a front elevational view;

FIG. 5 is a left rear isometric view as viewed from the top; and

FIG. 6 is a right front isometric view as viewed from the bottom.

The truck which is shown fragmentarily in broken lines is included for illustrative purposes only.

I claim:

The ornamental design for a sleeper van, substantially as shown and described.
